UNITED STATES PATENT OFFICE.

JOHN S. HOBSON, OF EDGEWOOD PARK, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-SIGNAL.

No. 926,743.

Specification of Letters Patent.

Patented July 6, 1909.

Application filed October 27, 1908. Serial No. 459,709.

To all whom it may concern:

Be it known that I, JOHN S. HOBSON, a citizen of the United States, residing at Edgewood Park, in the county of Allegheny and State of Pennsylvania, have invented certain new and useful Improvements in Railway-Signals, of which the following is a specification.

My invention relates to air buffers for rail-way signals and particularly to the semaphore type of railway signals each blade of which is used to give a plurality of indications, and irrespective if it is moved upwardly or downwardly on its pivot.

15 I will describe an air buffer embodying my invention and its application in a railway signal and then point out the novel features in claims.

In the accompanying drawings in which like reference characters designate similar parts in the respective figures, Figure 1 is a vertical sectional view of an air buffer embodying my invention. Figs. 2 and 3 are views similar to Fig. 1 but showing the parts 25 in different positions. Figs. 4, 5 and 6 are views, partly in section and partly in elevation, showing a semaphore signal in three different positions and an air buffer embodying my invention in its three different cor- 30 responding positions. In these figures certain details of construction are omitted.

Referring now to the drawings and particularly to Figs. 4, 5 and 6, the semaphore blade is designated by 10 and the spectacle 35 11. If the blade is moved from its horizontal position downwardly on its pivot to its inclined and vertical positions, the spectacle is made sufficiently heavy to always tend to move the blade to its horizontal position. If 40 on the other hand the blade is moved from its horizontal position upwardly on its pivot to its inclined and vertical positions, the weight of the blade and spectacle are both employed to return the blade to the horizontal posi- 45 tion. Both of these arrangements are well understood in the art, and my invention is applicable to either. The spectacle and blade are suitably fastened together and they are provided with a shaft 12 which is suitably 50 journaled, and arm 13 is provided, generally on the shaft 12, to which is connected the up and down rod 15 through which the blade is moved from its horizontal to its inclined and vertical positions. The up and down

rod 15 may derive its longitudinal movements from any desired type of motor. Its downward longitudinal movement may in some cases be obtained by its own weight and that of the parts connected to it when the rod is released from the position to which it 55 has been moved, or its downward movement may be obtained through the motor, in which case in automatic signals its upward movement is under the influence of the counterweight of the signal. In the drawings 60 I have shown the rod 15 connected with what is known in the art as a "slot arm" 16, which as usual is pivoted at one end, and provided with levers and electro-magnets by means of which its pivoted lever 16^a may be held rigid 65 and engage projections on a chain driven by a motor and thereby move the rod 15 upward. An illustration of this arrangement of parts is disclosed in United States Patent No. 611,943 granted October 4, 1898, upon an 70 invention of J. G. Schreuder. The downward movement of the rod 15 is cushioned to prevent shock and a buffer is employed for this purpose. My invention relates particu- 75 larly to the buffer, which is an air buffer and preferred forms thereof will now be described.

Figs. 1 to 6 illustrate one form which my invention may assume, and as will be seen, it comprises telescoping parts which are adapted to have successive movements ac- 80 cording to the movements of the blade 10.

Referring now particularly to Figs. 1, 2 and 3, 19 designates a part which serves as a piston, that is, it comprises a piston head 19^a and a hollow rod portion 19^b, the lower 85 end of which is adapted to be pivotally secured as at 20 to any suitable support, for example the framework supporting the signal operating mechanism. At or near the head 19^a is an annular groove 19^c or there 90 may be two oppositely arranged recesses or cut-outs, which coact with a locking device to be hereinafter described. 21 designates a second piston comprising a head 21^a and a hollow rod 21^b which slides in the hol- 95 low rod portion 19^b of the piston 19. The end of the rod 21^b is preferably provided with a packing ring. At or near the end of the rod 21^b oppositely arranged openings 100 21^c are provided in which are placed balls 105 22 having a diameter larger than the thickness of the wall of the rod 21^b.

23 designates a cylinder which is suitably

secured to a moving part of the signal operating mechanism for example the slot arm 16, such connection being designated 23^a. The cylinder which receives the heads 19^a, 5 21^a has connected with it a rod 23^b which projects into the rod 19^b and is movable therein. The rod 23^b is provided at its lower end with a packing ring or rings and intermediate its length with annular groove 10 23^c or there may be two oppositely arranged openings which coat with the balls 22. The balls 22 and the annular grooves 19^c and 23^c or oppositely arranged recesses as the case may be constitute a locking device. 15 by means of which the several parts of the air buffer may be moved successively. This perhaps will be better understood from a description of the operation of the device.

When the signal 10 is in its horizontal 20 position indicating "danger" or "stop" the parts of the air buffer are in the position shown in Figs. 3 and 6. If now the signal blade 10 is moved from its horizontal position to its inclined position (see Fig. 5) the 25 slot arm carries with it the cylinder 23, and piston 21, the cylinder and piston 21 being connected or locked together by the balls 22 which extend or project into the annular groove 23^c. When the blade 10 reaches its 30 final inclined position the parts are in the position shown in Figs. 5 and 2. In the event that the blade 10 is returned to its horizontal position the cylinder 23 and piston 21 will move to the position shown in 35 Figs. 3 and 6. If, however, the blade is moved to its vertical position (see Fig. 4), the movement of the cylinder 23 with the slot arm 16 through the rod 23^b causes the balls 22 to enter the annular recess 21^c thus 40 connecting or locking the pistons 19 and 21 together and leaving the cylinder 23 free to move independently of the pistons 19 and 21 after the blade has moved to its vertical position. The parts will then be in the 45 positions shown in Figs. 1 and 4. If the blade 10 is moved again to its inclined position, the cylinder 23 will return to the position shown in Figs. 2 and 5, which will bring the annular groove 23^c opposite the balls 22 so 50 that in the event of the blade 10 being moved to its horizontal position the cylinder 23 and piston 21 will be free to move to the position shown in Figs. 3 and 6. It will be seen that the pistons 19 and 21 will be 55 locked by the balls 22 during the movement of the cylinder 23 with the blade 10 from its vertical to its inclined position.

It will be understood, of course, that the 60 blade and the up-and-down rod are suitably supported against downward movement by suitable devices comprised in the signal operating mechanism except, of course, at such times as desired that the blade shall give different indications, and that the buffer mechanism embodying my invention is for

the purpose of cushioning the downward movement of the up-and-down rod 15 and parts connected therewith.

It is, of course, necessary to provide valves which will open freely for the admission of 70 air during the upward movement of the cylinders, and also to provide valves which will permit the air to escape slowly during the downward movement of the cylinders. These valves may be of any suitable or well 75 known construction. As shown I form a pocket 32 in the piston 21, which is provided with a seat for a ball valve 33. A similar pocket 34 is provided in the head of the cylinder 19 which also has a seat for a 80 ball valve 35. These valves will open freely to admit air when the cylinders are moved upwardly but will close under the pressure of air within the cylinders when the latter move downwardly. Strips of metal 36 project 85 over the pockets to prevent the balls being forced out of them.

38 designates an adjustable air vent provided in the cylinder 23.

Having thus described my invention, what 90 I claim as new is:

1. The combination with a signal blade, of means for moving it to a plurality of positions of indication, and an air buffer for cushioning the blade in its movements, said 95 air buffer comprising two pistons and a cylinder.

2. The combination with a signal blade, of means for moving it to a plurality of positions of indication, and an air buffer for 100 cushioning the blade in its movements, said air buffer comprising a piston having a hollow rod, a second piston also having a hollow rod which moves in the hollow rod of the first piston, and a cylinder having a rod 105 which moves in the hollow rods of both pistons.

3. The combination with a signal blade, of means for moving it to a plurality of positions of indication, and an air buffer for 110 cushioning the blade in its movements, said buffer comprising two pistons and a cylinder which have telescoping parts, and means for locking the cylinder with one of the pistons or the two pistons together in the successive 115 movements of the blade.

4. The combination with a signal blade, of means for moving it to a plurality of positions of indication, and an air buffer for cushioning the blade in its movements, said 120 buffer comprising two pistons and a cylinder which have telescoping parts, and means for locking the cylinder with one of the pistons or the two pistons together in the successive 125 movements of the blade, said means being operated and released by the movement of the parts of the air buffer.

5. The combination with a signal blade; of a cylinder connected therewith; a rod 23^b connected therewith; a piston 21 on which 130

said cylinder moves; a hollow rod 21^b for said piston through which said rod 23^b extends; a fixed piston 19 on which said cylinder also moves; a hollow rod 19^b into which the rods 23^b and 21^b extend; and means for at times holding the piston 21 immovable, relatively, to the piston 19; and other means for at times holding the piston 21 immovable relatively to the cylinder 23.

10 6. The combination with a signal blade, of air buffer for cushioning the blade in some of its movements; said buffer comprising a cylinder and two pistons which have telescoping parts; a connection between the cylinder and blade and a connection between one of the pistons and a fixed part; and means for locking the cylinder with one of the pistons, or the two pistons together in the successive movements of the blade, said means being 15 operated and released by the movements of the parts of the air buffer.

7. The combination with a signal blade, an air buffer for cushioning said signal blade in some of its movements; said air buffer comprising a cylinder connected with the signal blade, a rod carried by said cylinder and having an annular recess, a piston on which said cylinder moves, a hollow rod for said piston having an annular opening, a second piston 25 on which said cylinder also moves connected with a fixed support and having an annular recess; and balls arranged in the annular

opening of the hollow stem of the first piston, said balls coacting with the said recesses to lock together and release by movements of 35 the blade, the cylinder with one of the pistons or the two pistons.

8. The combination with a signal blade, an air buffer for cushioning said signal blade in some of its movements; said air buffer comprising a cylinder connected with the signal blade, a rod carried by said cylinder and having an annular recess, a piston on which said cylinder moves, a hollow rod for said piston into which said rod extends and said hollow 40 rod having an annular opening, a second piston on which said cylinder also moves, said second cylinder being connected with a fixed support and having an annular recess, a hollow stem for the second piston in which said 45 rod and the hollow rod of the first piston extends; and balls arranged in the annular opening of the hollow stem of the first piston, said balls coacting with the said recesses to lock together and release by movements of 50 the blade, the cylinder with one of the pistons or the two pistons.

In testimony whereof I have signed my name to this specification in the presence of two subscribed witnesses.

JOHN S. HOBSON.
